Primary Examiner — Rachel A. Voorhies*Assistant Examiner* — Benjamin D. Wannemacher(74) *Attorney, Agent, or Firm* — Polsinelli PC(57) **CLAIM**

The ornamental design for a cam, as shown and described.

DESCRIPTION

FIG. 1 is a front perspective view for a "wheel cap for an automobile" showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left-side elevation view thereof; and,

FIG. 8 is a right-side elevation view thereof.

The broken lines showing in the figures are included for the purpose of illustrating portions of the cam that form no part of the claimed design.

1 Claim, 4 Drawing Sheets---
